UNITED STATES PATENT OFFICE.

MILTON A. FESLER, OF OAKLAND, CALIFORNIA.

MEANS FOR REGULATING CENTRIFUGAL OIL-BURNERS.

1,117,652.

Specification of Letters Patent. Patented Nov. 17, 1914.

Application filed April 21, 1913. Serial No. 762,665.

To all whom it may concern:

Be it known that I, MILTON A. FESLER, a citizen of the United States, residing at Oakland, in the county of Alameda and State of California, have invented new and useful Improvements in Means for Regulating Centrifugal Oil-Burners, of which the following is a specification.

When for the purpose of heating a boiler or furnace, there is employed an oil burner supplied with oil by a pump operated by an electric motor, there are certain conditions, created by gross neglect and carelessness on the part of the attendant of the burner, under which the flames of the burner may become extinguished.

The object of the present invention is to provide means for automatically stopping the motor in such cases, thereby preventing the continuance of the supply of oil to the burner, and the consequent danger of a conflagration resulting therefrom.

In the accompanying drawing, Figure 1 is a side view, partly diagrammatic, of my improved apparatus; Fig. 2 is a detail plan view of a portion of said apparatus; Fig. 3 is an enlarged side view of a portion of said apparatus; Fig. 4 is a broken vertical section through the flue; Fig. 5 is a cross section on the line 5—5 of Fig. 4; Fig. 6 is a side view of a detail.

Referring to the drawing, 1 indicates a furnace having a flue 2 and in which a centrifugal oil burner 3 is rotated by an electric motor 4 and supplied with oil by a pipe 5 controlled by a valve 10 and leading from a pump 6 operated by said motor. Through a hole 7 in a side of said flue is passed an apertured projection 8 from a side of a housing 9, secured to said flue and spaced therefrom by asbestos or other insulating material 11. Secured by a set-screw 12 in the aperture in said projection is a cylindrical support 13, in one end of which is secured an open end of a brass or copper tube 14 the closed other end of which extends through a hole in the opposite side of the flue. Around said tube in said hole is asbestos packing 16, which packing lies also against the inner side of the flue, and between said

packing and the end of the projection 8 is an iron support 17 of stellate form, cut away, as shown at 18, to permit the hot gases to come in contact with the tube 14, but closely surrounding, and supported by, the tube between said cut-away portions. Abutting against the closed end of the tube is one end of a carbon rod 19, the other end of which carries a block 21 which can slide in said cylindrical support 13, and abuts against one side of a lever 22, pivoted at its upper end 23 to said support, against the other side of which lever abuts a block 24 pressed by a coiled spring 26 compressed between said block and a screw plug 27 screwed in said cylindrical support 13. From the lower end of said lever depends an elastic metallic rod 28, the lower end of which carries a contact knob 29. On the bottom of said housing 9 is an insulating block 31, on the top of which is secured, by a screw 32 and bolt 33, a flange or base 34 of a wall 36, said bolt passing through an enlarged hole in the bottom of the housing and having secured on its lower end an insulating washer 37 and nuts 38. Said bolt can thus form one terminal, insulated from the housing, but electrically connected to the wall, for an electric circuit, the other terminal of said circuit being electrically connected with the housing by a screw 39 screwed into the housing.

As shown in Fig. 2, said wall extends in a direction oblique to the plane of vibration of the lever 22, and has a front metallic surface 41 and a rear insulating surface 42. When a fire is started up in the furnace, the tube 14 expands to a much greater degree than the carbon rod 19, and the lever 22 moves to the left under the force of the spring 26. The knob 29, carried at the lower end of the rod 28, moving to the left, impinges against the rear insulating side of the wall, and is deflected rearwardly, moving along said rear side until it escapes past the edge of said wall, and the said electrical circuit remains broken between the knob and the wall. Said circuit remains open until the tube 14 contracts, whereupon the knob impinges against the front metallic side of

said wall, and the circuit is closed and remains closed during the contraction of the tube until the knob passes the right-hand edge of the wall.

5 To the terminal 39 is secured a wire 44, passing through an electric bell 45 and a condenser 46 to reduce the voltage of the current for the coil in the bell 45, and communicating through one side of a double pole main switch 47 with one side 48 of the line wire; and to the other terminal 33 is secured a wire 49 leading to the other side of said switch and connected thereby to the other side 51 of the line wire. Therefore, 10 when the circuit is closed, by abutment of the knob 29 against the conducting side 41 of the wall 36, the bell rings, and it continues to ring during the contraction of the tube 14 so long as the knob is in contact 15 with said side of the wall. From the wire 44 a wire 51 leads to an electro-magnet 53, a wire 15 leading therefrom to an electro-magnet 20, from which a wire 25 leads to a wire 54 which leads to a fuse 56 on one side 20 of a double throw switch 57, through said fuse and switch, then by a wire 58 leading from the same side to the wire 44 between the switch 47 and the condenser 46, then through the main switch 47 and by the wire 25 25 49 to the other terminal 33. Consequently, when the circuit is closed by the contraction of the tube the electro-magnets 53 and 20 are energized. The energization of the magnet 53 attracts an end of a lever 59, 30 pivoted at 61 on a frame 62, the other end of which is pivoted, as shown at 63, to an end of a link 64, the other end of which is pivoted to one arm of a bell crank lever 66, the other arm of which carries a hook 67, which engages a pin 68 on a hand lever 69, pivoted at 71 on said double throw switch. Therefore said bell crank lever is rocked and said pin 68 is released, and the switch is opened by a spring 72. This 40 switch is interposed in a circuit through the motor, as follows:—from one side 48 of the line wire, by the wires 44, 58, to one side of the double throw switch 57, through said side and fuse, then by wires 54, 73 to a contact 74 of said switch, then by a wire 76 to the electric motor and wire 77 to the other contact 78 of said double throw switch, then by a wire 79 to the other fuse 81 thereof, and through the latter side of the switch 50 and by wires 82 and 49 to the other side of the line. Therefore, when the switch is opened, the circuit through the motor is broken and the motor stops. This of course does not affect the ringing of the bell, 55 which continues for a period of several minutes, during which the knob 29 is in sliding contact with the metallic surface of the wall 36. The energization of the magnet 20 attracts an arm 92 of a lever 93, another arm of which is formed with a hook

94. Thereby said hook is withdrawn from engagement with an arm 95 connected with the valve 10. A weight 96 in said arm 95 thereupon actuates said valve to close the pipe 5.

When the circuit through the motor is again closed by moving the double throw switch into the position shown in Fig. 1, a shunt circuit is also closed around a solenoid 86 as follows:—from the wire 54 by a wire 87 through the solenoid, then by a wire 89 to the wire 92. Thereby the solenoid is energized to raise its core 90, the lower end of which is connected by a link 91 with the joint 63. Therefore the bell crank lever 66 is restored to its normal position in which the hook 67 engages the pin 68.

I claim:—

1. The combination of a centrifugal oil burner, an electric motor for rotating said burner, a thermostat arranged to be heated by the products of combustion of said burner, and means, arranged to be actuated by the cooling of said thermostat, for arresting said motor.

2. The combination of an oil burner, an oil supply pump, an electric motor for operating said pump, a thermostat arranged to be heated by the products of combustion of said burner, a device to control the circuit through the motor, and means for actuating said device arranged to be operated by the cooling of said thermostat.

3. The combination of an oil burner, an oil supply pump, an electric motor for operating said pump, a thermostat arranged to be heated by the products of combustion of said burner, an electric circuit arranged to be changed by the cooling of said thermostat, electro-magnetic means in said circuit, and a device actuated by the electro-magnetic means to control the circuit through the motor.

4. The combination of an oil burner, an oil supply pump, an electric motor for operating said pump, a thermostat arranged to be heated by the products of combustion of said burner, an electric circuit arranged to be closed by the cooling of said thermostat, electro-magnetic means in said circuit, a switch for controlling the circuit through the motor, a spring for opening said switch, a latching device for maintaining said switch closed, and a device actuated by the electro-magnetic means when energized to withdraw said latching device.

5. The combination of an oil burner, an oil supply pump, an electric motor for operating said pump, a thermostat arranged to be heated by the products of combustion of said burner, an electric circuit arranged to be closed by the cooling of said thermostat, electro-magnetic means in said circuit, a switch for controlling the circuit through the motor, a spring for opening said switch,

a latching device for maintaining said switch closed, a device actuated by the electro-magnetic means when energized to withdraw said latching device, a conductor closed by the cooling of said thermostat, wires leading from opposite sides of said conductor to the line wires, and a condenser and electric bell in the circuit thus formed.

In testimony whereof I have hereunto set my hand in the presence of two subscribing witnesses.

MILTON A. FESLER.
